UNITED STATES PATENT OFFICE.

JOHN LINCOLN GISH, OF SOUTH BEND, INDIANA.

REGULATED AUTOMATIC-CLOSING VALVE.

No. 892,987.

Specification of Letters Patent.

Patented July 14, 1908.

Application filed May 18, 1905. Serial No. 261,059.

To all whom it may concern:

Be it known that I, JOHN L. GISH, a citizen of the United States, residing at South Bend, in the county of St. Joseph and State of Indiana, have invented a new and useful 5 Regulated Automatic-Closing Valve, of which the following is a specification.

My invention relates to a regulated automatic closing valve.

10 The object of my present invention is to construct a "regulated automatic closing valve" in such a manner that, the time, may be governed or controlled, in which the automatic closing valve, is closed, as hereinafter 15 described.

Figure 1, is an elevation of a "regulated automatic closing valve", provided with my improvements. Fig. 2, is a vertical section thereof, with the valve A closed. Fig. 3, is a 20 vertical section thereof, with the valve A open.

Like letters of reference, refer to like parts, in the several figures.

In Fig. 2, we have the motor or power wheel, R, upon which are fastened buckets 25 or paddles, (O, O, O) in the nature of a paddle-wheel. The power wheel, R, is in contact with the gear-wheel, S, which in turn, is in contact with the lock-wheel, T. In the lock-wheel, T, there is a slot or depression, V, 30 which receives a part of the stem E, and the stem E, is the connecting rod, between the button, G, and the valve. In Fig. 2, the valve A, is in close and direct contact, with its seat, A', (Fig. 2); thus making a complete 35 closure and preventing all fluids, from passing forward, through the passageway, Z and Z', and escaping through the opening at C, (Fig. 2.) B, B, is the valve casing provided with the inlet passage at X, and the 40 outlet passage at C. In the drawings, a self closing valve of the reciprocating type is shown.

In Fig. 3, by pressure upon the button, G, the stem, E, is released from the slot, V, in 45 the lock-wheel, T, and at the same time the valve, A, is pushed away from direct contact, with its seat, thus making a free space upon all sides of the valve, A, (Fig. 3), and allowing fluids, to pass forward, through the 50 passage way, Z and Z' and escape through the opening at C (Fig. 3.) As soon as the fluids, are allowed to enter the passageway Z and Z', they come in contact with the buckets or paddles, (O, O, O) on the power 55 wheel, R, thus causing the power wheel, R, to revolve; which in turn, by means, of the

gear-wheel, S, revolves the lock-wheel, T. The lock-wheel T, having changed its position, and moved the slot, V, away from the stem E; the valve is now held open, at A', 60 by means of the stem E, resting upon the rim of the lock-wheel T, and the valve will remain open, until the lock-wheel T, revolves upon its axis, and brings the slot, V, into such position, that the pressure of the 65 fluids, against the valve, can force the stem E, into the slot V, and at the same instant, automatically close the valve.

By increasing or decreasing the size, speed, or gearing of the wheels, R, S, and 70 T, the time may be regulated, in which the automatic closing valve, is closed, as above described.

In my invention the function and use of the lock-wheel T, is to hold the self closing 75 valve open and to release the same at a pre-determined time. No intermediate parts or mechanism, such as pawls or levers being used or required, between said valve and wheel T, in order to complete the function or 80 use of my wheel T. In my invention, without the use of pawls or levers, or their equivalent, my wheel T, forms the direct locking and the direct releasing mechanism, by some part of the valve-stem, or projection 85 upon the same, coming in contact with and forming a continuous movable contact of surfaces, upon a rim or outer band on the lock-wheel T. In such relation of parts the self closing valve is held in the open position, until the lock-wheel T, actuated by the power wheel R, revolves upon its axis and 90 brings the slot, V, or depression, (contained in said rim or band on lock-wheel T), under the continuous movable contact surface of 95 the valve-stem, or projection upon the same, when the self closing valve is released instantly. Thereby making my wheel T, (without any intermediate parts, between 100 said valve and wheel T), distinctively the direct lock and the direct release, for and between the self closing valve.

What I do claim as my invention and desire to secure by Letters Patent is,—

1. In a regulated automatic closing valve, 105 the combination of a valve casing provided with the inlet and outlet passages, a power wheel in the casing adapted to be operated by fluid passing through the casing, a gear wheel moved by said power wheel, a wheel T 110 moved by the gear wheel, a reciprocating valve, and means contacting with the pe-

riphery of the wheel T and operating the valve, whereby the latter may be kept open for a predetermined time.

2. In a regulated automatic closing valve 5 operated by fluid passing through the valve casing,—a wheel T having a slot V, and mechanism coöperating therewith, to allow closure of the valve.

3. In a regulated automatic closing valve 10 operated by fluid passing through the valve

casing,—a wheel T having a slot V, adapted to coöperate with the valve stem, to allow closure of the valve.

In testimony whereof I have signed my name to this specification in the presence of 15 two subscribing witnesses.

JOHN LINCOLN GISH.
